UNITED STATES PATENT OFFICE.

ROBERT B. SMITH, OF STOUGHTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR SETTING FASTENERS.

1,371,329.

Specification of Letters Patent. Patented Mar. 15, 1921.

Application filed July 11, 1917. Serial No. 179,962.

To all whom it may concern:

Be it known that I, ROBERT B. SMITH, a citizen of the United States, residing at Stoughton, in the county of Norfolk and 5 State of Massachusetts, have invented certain Improvements in Machines for Setting Fasteners, of which the following description, in connection with the accompanying drawings, is a specification, like reference 10 characters on the drawings indicating like parts in the several figures.

This invention relates to machines for setting fasteners and is illustrated as embodied in a machine especially adapted for handling the supplementary parts of compound fasteners, in this case gromets and washers. As will later appear, certain features of the 15 invention are equally applicable to machines for setting or inserting other fasteners of 20 this class such as rivets and burs, the parts of a ball and socket fastener, and the like.

Many machines for setting compound fasteners are so constructed and arranged that it is necessary to position manually one or 25 both of the parts of a fastener in operative relation to the setting or inserting instrumentalities. It is obvious that such manual intervention results in greatly decreasing the speed of operation and at the same 30 time materially increases the possibility of injury to the operator.

One object of the invention is to provide an improved machine especially organized to present the supplementary parts of a 35 compound fastener to operative position and apply them to the work to the end that manual intervention, with its attendant disadvantages, is avoided.

In many machines heretofore used for 40 setting compound fasteners the work has been shifted manually from one fastener-receiving position to the next, instead of being fed by automatic mechanism. This has been due to the fact that the greater portion of articles to be provided with such 45 fasteners require so few fasteners, or require so great spacing between them, that it has not been feasible to encumber the machines with automatic feeding mechanism. The foregoing conditions apply to such articles 50 as sails, tents, blankets, floor-coverings and awnings. On the other hand, some articles such as military belts, leggings, and heavy boots require compound fasteners at

comparatively short and regular intervals. 55 Another object of the invention, therefore, is to provide an improved machine for setting or inserting compound fasteners in which the machine shall feed the work to effect the desired spacing between the successive 60 fasteners, it being immaterial whether or not the feeding operation is conjoint with the presentation of the parts of the fasteners to setting position.

Still another object of the invention is to 65 provide a machine for applying annular members in which the lateral movement of the element of the machine which is arranged to engage the work to feed it will be utilized for removing an annular member 70 from a fixed raceway and for transferring it into operative relation, for example, to the setting devices.

In the illustrated embodiment of the invention, the work is fed by a member associated with one of the setting devices and this member is utilized also for removing an annular member, for example, a washer, 75 from a raceway. A hole is formed in the work by means of a punch which is preferably arranged to pass through the lower-most washer in the raceway in order to punch the hole, after which the punch is withdrawn and the feeding member is passed through the washer and inserted into the 80 punched hole as a step precedent to feeding the work.

Other features will be apparent from a consideration of the following description of an illustrative embodiment of the invention in a machine especially designed for setting gromets and washers. This description refers to the accompanying drawings in which,—

Figure 1 is a perspective view of the punching and setting instrumentalities, together with the raceways for supplying fasteners thereto;

Fig. 2 is a view of the completed work; and

Figs. 3 to 6 show successive steps in the operation of the machine.

The particular construction and arrangement of the punching and setting instrumentalities is not essential to this invention 105 but they are here shown, for example, as embodied in a machine of the type illustrated in Letters Patent No. 603,023 granted

upon an application of Seymour Field, on April 26, 1898. To this end there is shown a supporting frame 10 mounted upon which is a work plate 12. Mounted in bearings 5 upon this frame is an axially reciprocable lower set bar 14 in which is clamped the setting device 16 provided with the usual spring-pressed center spindle 18. The other setting device is adjustably mounted upon 10 the top set lever 20 and will be seen to constitute a top set 22 of usual construction provided with a projecting pilot 23. A punch 24 is carried upon a punch lever 26 and a presser foot 28 resiliently holds the work against the table 12 but may be raised 15 and to allow feeding movement of the work at the desired time.

A gromet raceway 30, of usual construction and having a retaining finger 31, may 20 be operated in the fashion described in the above-mentioned patent to deliver gromets to the spindle 18 of the lower set and then move out of alinement as the lower set is raised to operative position. In addition, 25 there is provided a raceway 32 for the annular members constituting supplementary parts of the compound fasteners, as, for example, the washers 34, here shown as of the barrel type, which are to be engaged by the 30 outwardly flanged portion 36 of the gromets 37 when the same are set in the work. (See Fig. 2). This raceway is of a similar construction to the raceway 30 and is provided with rails 38 for supporting the flange of 35 the washer and guiding its barrel. At the lower end, there is provided a spring-retaining finger 40 of the common type which acts as a stop for the washers in the raceway but permits the lowermost washer to be removed 40 during the operation of the machine. This raceway is constructed and arranged so that the lowermost annular member therein is threaded by the punch in its movement to punching position against the punch block 45 27 and to this end the cover plate of the raceway is notched at 42, as shown in Fig. 1. An adjustable edge gage 44 is provided upon the work table 12.

The operating parts are shown in their 50 rest position in Fig. 3, from which it will be seen that the two setting devices 16 and 22 are in alinement and that the punch 24 is over the end of the raceway 32. As a first step, the punch 24 descends, as shown 55 in Fig. 4, and, threading the washer 34 at the end of the raceway 32, it pierces the work 50 which has been placed upon the table 12 beneath the presser foot 28 and against the edge gage 44. At this time, the lower set 16 has commenced to descend and the raceway 30 is moving forward to the position shown in Fig. 5, so that the lowermost gromet yieldingly retained by the finger 31, is directly above the spindle 18 60 upon the lower set. The next step in the op-

eration is represented in this figure and it will be seen that the punch 24 has been lifted away from the table and the work and has moved to one side while the upper set 22 has moved laterally and descended so that the 70 projecting pilot 23 thereon has threaded the lowermost washer in the raceway 32 and the hole in the work. It will be understood that in the arrangement of the machine described in the above-mentioned patent, the movements of the upper set and the punch transversely of the work table are concurrent but this is not an essential feature of this invention. The lower set 16 then rises and picks off the lowermost gromet in the raceway 30 which retreats in a well understood fashion. At the same time, the upper set 75 22 moves laterally into alinement with the lower set carrying with it the washer 34 and the work. When the two sets are in alinement, they are brought together so that the washer is positioned on the barrel of the gromet and the gromet set in the usual fashion to give the finished product illustrated in Fig. 2. The upper and lower sets then 80 separate and return to the rest position indicated in Fig. 5, after which the operation 85 described may be repeated.

It will be noted that the delivery of the supplementary parts of the fasteners to the 90 setting devices is entirely automatic and that owing to the use of a washer which is provided with a barrel projection such as is described in Patent No. 1,163,112 issued upon an application of Walter Shaw, it is 95 possible to deliver the washers from a hopper to the raceway in an exactly similar fashion to the well understood delivery of eyelets or gromets from a hopper to a raceway. Adjustment of the length of feed 100 by any suitable mechanism such as is described in the above-mentioned patent to Field will necessitate the adjustment of the position of the raceway 32 so that the lowermost fastener therein shall be in position to 105 be threaded by the punch as it descends to operate upon the work.

Having thus described my invention, what I claim as new and desire to secure by Letters Patent of the United States is: 115

1. In a machine of the class described, two raceways for supplying the complementary parts of two-part fasteners, and two co-operative setting devices arranged to transfer the complementary parts of a fastener 120 from the raceways respectively to a clenching locality, one of said setting devices having a pilot and being movable to insert the latter through a fastener part and into the work while said fastener part is in its raceway and thereafter being movable laterally 125 to feed the work and to transfer the said fastener part to the clenching locality.

2. In a machine of the class described, an axially movable setting device, a raceway 130

movable into the path of said setting device, a coöperating setting device provided with a projecting member and arranged for axial setting movement and lateral feeding movement to feed the work by reason of the engagement of said projecting member therewith, and a fixed raceway for annular members positioned and arranged so that the projection upon said setting device will 5 thread the lowermost annular member in the raceway as it moves to engage the work and will remove said member from the raceway as it moves to feed the work.

3. In a machine for setting compound fasteners, a setting die, means for supplying one kind of parts of said fasteners to said die, a punch, a raceway for supplying the supplementary annular parts of said fasteners arranged so that the lowermost annular part will be threaded by the punch during the punching operation, and a setting device arranged to engage said lowermost annular part and a hole in the work, said latter setting device being movable laterally to feed the work and the annular part and movable axially to coöperate with the other setting device in attaching the parts of the compound fastener to the work.

4. In a machine for setting gromets and washers, a lower setting die, means for supplying gromets to said die, a punch, a raceway for washers arranged so that the lowermost washer will be threaded by the punch during the punching operation and an upper set arranged to engage the lowermost washer and a hole in the work, means for moving the same laterally to feed the work and the washer, and means for moving said set axially to assist in setting the gromet 30 and the washer in the work.

5. Fastener - inserting mechanism comprising a setting device having a pilot portion, and mechanism arranged to move it endwise into the work and then laterally to feed the work, and a raceway arranged to present a fastener to said device in registration with the lines of endwise movement along which the device moves to enter the work.

6. Fastener - inserting mechanism comprising a fastener-engaging tool, a raceway arranged to supply annular fasteners to said tool, and mechanism arranged to operate said tool so as to cause it to impale a fastener 55 and an article of work while the fastener is in said raceway and thereafter to feed the work and detach the impaled fastener from the raceway.

7. In a machine of the class described, 60 raceways for annular members, a punch arranged to make holes in the work in predetermined relation to the endmost annular member in one of the raceways, and a setting device having a member arranged to thread the endmost annular member in the raceway

and a hole formed in the work by said punch and mechanism for moving said setting device laterally to remove the annular member from the raceway and bring it to attaching position and to feed the work. 70

8. In a machine for attaching compound fasteners, a work-feeding and fastener-setting tool, a setting tool arranged to coöperate therewith, mechanism arranged to move the first said tool into the work then laterally to feed the work, and raceways for supplying fasteners to the tools respectively, the raceway for supplying the feeding tool being arranged to support the leading fastener in concentric relation to the feeding tool as the latter enters the work, so that the subsequent lateral movement of that tool will remove the fastener from the raceway while feeding the work. 75

9. In a machine for attaching compound fasteners one part of which is an annular member, raceways for the respective parts of said fasteners, coöperating setting devices, one of said devices being only movable axially and the other device being movable axially and laterally, and mechanism constructed and arranged to effect the removal of the supplementary parts of a compound fastener from the raceways by causing relative movement of the setting devices and the raceways and to effect the feeding of the work by a lateral movement of one of the setting devices transversely to its axis. 80

10. A machine for setting compound fasteners, raceways for the parts of said fasteners, a punch arranged to make a hole in the work in predetermined relation to the endmost fastener in one of said raceways, and setting devices arranged to engage the endmost fasteners in the respective raceways 100 and remove the same and set them in the work, one of said setting devices being arranged to engage one of the fasteners and the related hole in the work and movable laterally to feed the work and the associated fastener. 105

11. In a machine for attaching compound fasteners, two coöperative setting tools one of which is movable relatively to the other to feed the work, and raceways arranged to supply coöperative parts of a compound fastener to said tools respectively, the delivery ends of the raceways being offset laterally from alignment with each other and the feeding tool being arranged to transfer a fastener part from one of the raceways to coaxial registration with the other tool. 110

12. In a machine for attaching compound fasteners, two coöperative setting tools one of which is movable relatively to the other to feed the work, and raceways arranged to supply coöperative parts of a compound fastener to said tools respectively, said feeding tool and the raceway by which it is supplied being so constructed and arranged that 125

a fastener part is transferred from the raceway to attaching position by feeding movement of the tool.

13. In a machine for attaching annular fasteners, two coöperative setting tools one of which is movable laterally to feed the work, and a raceway arranged to supply fasteners to the feeding tool, the latter being arranged and operated to transfer, by its work feeding movement, a fastener from the raceway to the work.

14. In a machine for attaching annular fasteners, a setting tool having a pilot portion, a raceway for supplying fasteners to said tool, means arranged to move said tool in one direction so as to insert the pilot portion through a fastener and into the work while the fastener is in the raceway, means

for moving said tool laterally to feed the work and to remove the fastener from the raceway, and another setting tool arranged to coöperate with the aforesaid setting tool.

15. In a machine for attaching annular fasteners, a raceway for supplying fasteners, a work-feeding tool formed and arranged to impale the leading fastener in the raceway, mechanism arranged to move said tool in one direction to impale the fastener and to enter the work while the fastener is in the raceway and in another direction to feed the work and simultaneously to detach the impaled fastener from the raceway, and means for attaching the fastener to the work.

In testimony whereof I have signed my name to this specification.

ROBERT B. SMITH.
